UNITED STATES PATENT OFFICE.

LOUIS ZWEIG, OF BROOKLYN, NEW YORK, ASSIGNOR TO SUN RISE LAMP MFG. CO., INC., A CORPORATION OF NEW YORK.

DESIGN FOR A LIGHTING APPLIANCE.

Application filed May 2, 1929. Serial No. 31,081. Term of patent 3½ years.

To all whom it may concern:

Be it known that I, LOUIS ZWEIG, a citizen of the United States, and a resident of the city of Brooklyn, county of Kings, and State of New York, have invented a new, original, and ornamental Design for a Lighting Appliance, of which the following is a specification, reference being had to the accompanying drawing, forming a part hereof.

In the drawing:

Figure 1 is a perspective view of the lighting appliance, which has a central body A and a plurality of upwardly and outwardly extending arms B for the support of glass panels C; and

Figure 2 is an inverted plan view of the same, showing the body and arms, the glass panels being omitted; the parts shown in full line outline being ornamented in the same manner as the parts more fully illustrated.

I claim:

The ornamental design for a lighting appliance substantially as shown and described.

LOUIS ZWEIG.
